Attorney

UNITED STATES PATENT OFFICE.

HENRY F. KELLNER, OF SILVER LAKE, KANSAS.

SILT ACCUMULATOR.

Application filed August 8, 1921. Serial No. 490,566.

To all whom it may concern:

Be it known that I, HENRY F. KELLNER, a citizen of the United States, residing at Silver Lake, in the county of Shawnee and State of Kansas, have invented certain new and useful Improvements in Silt Accumulators, of which the following is a specification.

This invention relates to a silt accumulator of the class adapted for use in protecting the banks or changing the direction of currents of silt-bearing streams, and has for its object, broadly, to provide such a construction for the silt accumulator that it may be manufactured conveniently and economically, and will be effective in use. One of the specific objects in view is to provide a base which will become covered with silt, to prevent overturning or displacement.

In the accompanying drawing, Fig. 1 is a perspective view illustrating the use of the silt accumulators in a stream. Fig. 2 is a perspective view of the silt accumulator. Fig. 3 is an end view and Fig. 4 is a side view of the silt accumulator, the inclined strands at the front of the standards being omitted.

Referring now particularly to the drawing, I provide a rectangular, horizontal foundation base 5 consisting, in part, of approximately rectilinear supports or strips 6 disposed side-by-side in spaced relation and approximately parallel, strips 7 being employed and disposed in engagement with and approximately at right-angles to the strips 6, and having end portions *a* which extends outwardly from or beyond the sides of the strips 6, said strips 6 having end-portions *b* which extend outwardly from or beyond the sides of the strips 7, the intersecting parts of said strips 6 and 7 being suitably secured together as indicated at 8. The remaining part of the base consists of wire mesh 9 which is secured to the strips mentioned.

However any suitable material through

which water may readily pass may be substituted for the wire mesh 9.

Numerical 10 indicates standards or upright strips which are secured at their lower ends to the horizontal strips 6 and 7 at their intersections, some of the standards being disposed at the edges of the wire mesh. Said standards may be of any suitable height, depending upon the depth of the water in which the silt accumulators are to be used.

The remaining parts of the silt accumu-

lator consists of certain strands which operate to deflect a current of water and to maintain the standards at approximately right-angles to the strips 6 and 7.

The standards 10 are connected at their upper ends, strands 11 and 12 being employed for this purpose, the strands 11 being disposed above and approximately parallel with the base-strips 6, and strands 12 being disposed above the base-strips 7; and the top of each standard, at the ends of the silt accumulator is connected with the end of an extension *b* of a strip 6 by a strand 13; and strands 14 connect the ends of the extensions *a* of the strips 7 with the tops of the standards at the sides of the base 5.

Numerals 15 and 16 indicate secondary strands which connect the standards midway between their ends, strands 16 being disposed below and in the plane of the strands 11, and strands 15 being disposed below and in the plane of strands 12; and the standards at the ends of the silt accumulator are connected midway between their ends with extensions *b* of the strips 6 by strands 17; and strands 18 connect the extensions *a* of strips 7 with the standards at the sides of the base 5, midway between the ends of the standards.

Since the strands 13, 14, 17 and 18 are disposed inclinedly, they aid materially in resisting stresses directed to the standards by swift moving waters, as well as operating to deflect water currents.

In operation, the silt accumulator may be placed in a stream to cause sand deposits in the bed "down stream" therefrom, and they may be connected end-to-end as shown in Fig. 1 and connected with the bank by a cable *c* or other suitable means for protecting the banks of streams, or for controlling the direction of water currents.

Among some of the advantages to be derived by use of the herein described silt accumulator, it may be stated that the parts are few and simple and may be conveniently produced. The standards 10 may be maintained in an upright position and, together with the strands mentioned will operate to deflect the water to advantage, the wire mesh 9 being covered with silt tending to prevent displacement.

It will be understood that changes in size, proportion and minor details may be made, said changes being within the scope of the invention as claimed.

I claim as my invention:

1. In a silt accumulator, a rectangular, foraminous sheet, a plurality of strips disposed at right angles in engagement with each other and connected with the sheet, each strip having end portions projecting outwardly of the edges of the sheet, a plurality of standards secured to the intersecting parts of the strips, strands connecting the upper end of each standard with the upper end of each standard adjacent thereto, strands connecting each standard midway between its ends with the middle of each standard adjacent thereto, a plurality of strands each connecting an end portion of a strip with the top of a standard, and a plurality of strands each connecting an end portion of a strip with the middle part of a standard.
- 10 2. A silt accumulator, comprising a rectangular, foraminous sheet, strips disposed at right angles to and in engagement with each other and connected with the sheet, each

strip having end portions projecting outwardly from the edges of the sheet, standards secured to the intersecting parts of the strips, strands connecting the upper end of each standard with the upper end of each standard adjacent thereto, strands connecting each standard midway between its ends with the middle of each standard adjacent thereto, a plurality of strands each connecting an end portion of a strip with the top 30 of a standard, and a plurality of strands each connecting an end portion of a strip with the middle part of a standard.

In testimony whereof, I have affixed my signature in presence of two witnesses.

HENRY F. KELLNER.
